UNITED STATES PATENT OFFICE.

THADDEUS STEPHENS CASNER, OF PLAINFIELD, NEW JERSEY.

SUPPORTING-LEG FOR WASHTUBS.

1,337,997.

Specification of Letters Patent. Patented Apr. 27, 1920.

Application filed September 4, 1919. Serial No. 321,561.

To all whom it may concern:

Be it known that I, THADDEUS S. CASNER, a citizen of the United States, and a resident of Plainfield, in the county of Union and State of New Jersey, have invented certain new and useful Improvements in Supporting-Legs for Washtubs, of which the following is a specification.

My invention relates to wash tubs and particularly to a detachable leg for supporting a tub in elevated position.

It is the purpose of my invention to provide a detachable tub leg of simple and efficient construction having means associated therewith for rigidly gripping and supporting the tub, which is adjustable to accommodate tubs of various heights.

I will describe one form of leg embodying my invention and will then point out the novel features thereof in claims.

In the accompanying drawings:

Figure 1 is a view, showing in perspective a wash tub having applied thereto one form of leg embodying my invention;

Fig. 2 is a fragmentary view of the tub shown in Fig. 1, with the supporting leg in front elevation;

Fig. 3 is a view similar to Fig. 2, showing the leg in side elevation; and

Figs. 4 and 5 are detail views of the invention.

Similar reference characters refer to similar parts in each of the several views.

Referring specifically to the drawings, and particularly to Fig. 1, T designates a wash tub of the usual construction, including a tapered body 15 having an annular bead 16 formed on the upper edge thereof, and a depending annular flange 17 formed on its lower edge.

The legs which constitute the subject-matter of my invention are each designated generally at L, and each comprises a shank portion 18, preferably formed of wood and which is preferably rectangular in cross section. Secured to the inner face of the shank 18 is a wedge-shaped block 19, which is formed of the same material as the shank and extends from the upper end thereof to a point substantially medially of the same. Secured to the outer face of the shank 18, at a point between the ends of the wedge 19, is a rack bar R, which comprises a plurality of up-turned teeth 20 separated by intervening notches 21. This rack bar R is preferably cast or stamped from a single

length of metal, the opposite ends thereof being flat and formed with openings to receive fastening members 22. These fastening members 22 also serve to secure the opposite ends of a substantially U-shaped yoke Y, which has its medial portion arranged in spaced parallel relation to the rack bar R so as to function as a guard plate and to confine a supporting bracket B in operative relation to the rack bar, as will be herein-after described. The bracket B is formed from a single length of wire bent in the form of a U, as clearly shown in Fig. 4 of the drawings. The ends of the bracket B are bent upon themselves to provide hooks 23, which are adapted to engage the flange 17 of the tub, as shown in Fig. 3. The medial portion of the bracket B is adapted to seat within any one of the notches 21 of the rack bar R, while the parallel portions of such bracket are arranged upon opposite sides of the shank 18. From this arrangement, it will be seen that the yoke Y serves to confine the medial portion of the bracket upon the rack bar R at the same time permitting the bracket to be adjusted to seat within any one of the notches 21.

Formed adjacent the upper end of the shank 18 is an opening for loosely receiving the free ends of a link D, so as to pivotally support the same upon the shank 18. The link D is formed from a single length of wire which is bent in the form of a rectangle with the side portions thereof tapering outwardly to accommodate the side portions of a gripping member G, as clearly shown in Figs. 2 and 5. The lower end of the link D is adapted when in its active position to seat within a groove or notch 24 formed on the outer face of the shank 18 and to thereby lock the gripping member G against upward movement, as will be hereinafter described.

The gripping member G is formed from a single length of resilient wire which is bent longitudinally in the form of an arc, its upper end terminating in a reverse bend to provide a hook 25, while the lower free ends thereof are bent upon themselves to provide eyes 26 for loosely receiving the lower end of the link D.

In the applied position of each leg L, the block 19 contacts with the inclined side wall of the body 15, so that the shank 18 as well as the tub T assumes a vertical position. The bracket B is now arranged so

that the hooks 23 engage the flange 17, and when three of the legs are applied to a tub, as shown in Fig. 1, the brackets B of each leg coact to support the tub in elevated position. Each gripping member G is now swung downwardly, so as to cause the hook 25 to engage the bead 16 while the lower end of the link D moves into the notch 24 and thereby locks the member G against upward movement. During this movement the link D and the member G acting together form a toggle, the link D being under compression and the member G under tension when in active position. As the lower end 15 of link D swings down to its lowermost position, the tension on member G gradually increases until the lower end of link D is on a line projecting through the top flange 16 of the tub and fulcrum point of the link D, 20 thereby securing the desired locking effect. A slight further movement of the lower end of the link D toward the tub carries it over dead center and automatically locks and holds the link and member G in active position. During the movement of the gripping member to the active position, the tub is forced downwardly against the hooks 23, and because of the fact that the gripping member G is formed of resilient material, it 25 is held under tension when in applied position so as to firmly grip the tub. Should not the distance between the bead 16 and the flange 17 correspond to the distance between the hook 25 and the hooks 23, the bracket 30 B is adjusted vertically upon the rack R until these distances are approximately equal so as to firmly grip the tub and support the same in elevated position. Should the space between any two adjacent teeth 35 20 be greater than the required adjustment of the bracket B to effect a firm grip of the tub, the gripping member G being formed of resilient material and curved, will be extended or sprung longitudinally to a small degree when moving the member into gripping position so as to provide the necessary space for the reception of the tub. From 40 this operation, it will be seen that I provide the necessary adjustment to accommodate 45 tubs of various heights, that is, within reasonable limits, and that in any adjusted position of the bracket B the gripping member G effectively coacts with the bracket to firmly grip the tub and hold the same in 50 proper position upon the shank 18.

Although I have herein shown and described only one form of supporting leg

embodying my invention, it is to be understood that various changes and modifications may be made herein without departing 60 from the spirit of the invention and the spirit and scope of the appended claims.

Having thus described my invention, I claim:

1. A supporting leg for tubs comprising 65 a shank, a bracket on the shank and adapted to engage the lower edge of the tub, a link pivoted on the shank above said bracket for outward swinging movement, and a gripping member pivotally connected to said 70 link at its lower end and having its upper end bent to provide a hook for engaging the upper edge of a tub.

2. A supporting leg for tubs comprising 75 a shank, a wedge block secured to the inner face of said shank, a rack bar secured to the outer face of said shank and formed with upwardly-extending teeth, a supporting bracket adjustable on said rack bar and formed with hooks adapted to engage the 80 lower edge of the tub, a yoke carried by said rack bar for confining said bracket upon the bar, and pivoted gripping means carried by said shank which is movable to force the tub downwardly against said bracket and to 85 hold the same against said shank.

3. A supporting leg for tubs comprising a shank, a bracket on said shank and adapted to engage the lower edge of a tub for supporting the same upon said shank, a link pivoted on the shank, a gripping member pivotally connected to said shank, and curved longitudinally in the direction of the shank and bent at its upper end to provide a hook, and a notch formed in said shank 95 below the pivot point of said link for receiving the latter to lock the member in applied position.

4. A supporting leg for tubs comprising 100 a shank, supporting means on said shank adapted to engage the lower edge of a tub, and a toggle on said shank movable to engage the upper edge of a tub and to force the latter against said bracket.

5. A supporting leg for tubs comprising 105 a shank supporting means on said shank adapted to engage the lower edge of a tub, a link pivoted to said shank, and a gripping member pivoted at one end to the free end 110 of said link and formed at its opposite end with a hook which is adapted to engage the upper edge of a tub.

THADDEUS STEPHENS CASNER.
